C. BAEHR

TIN CAN OPENER

Filed May 25, 1925

UNITED STATES PATENT OFFICE.

CHARLES BAEHR, OF LE LOCLE, SWITZERLAND.

TIN-CAN OPENER.

Application filed May 25, 1925. Serial No. 32,812.

To all whom it may concern:

Be it known that I, CHARLES BAEHR, citizen of the Confederation of Switzerland, residing at Le Locle, Switzerland, have invented certain new and useful Improvements in Tin-Can Openers, of which the following is a specification.

The present invention relates to a tin can opener of the kind of tools which are adapted to open a tin can by cutting into the sheet metal.

The annexed drawing represents one working form of the object of the invention, to wit, in

- 15 Fig. 1 an elevation, in
 Fig. 2 a cross-section on line II—II of
 Fig. 1 and in
 Fig. 3 a section on line III—III of
 Fig. 1,
 20 Fig. 4 is a view of an auxiliary tool and
 Fig. 5 illustrates the manner of using the
 tool.

In the drawing a steel blade 1 shaped like a bird's head with a half opened hook bill is provided with a sharp edged upper jaw 4 and a toothed lower jaw 5 and with a sharp edged pricking blade 3 arranged like a cock's comb. This blade is held by an outwardly bent handle 6 which is riveted unto said blade at its contracted fore end. This handle is made of a strip of sheet iron bent so as to present a U-shaped cross section.

In using this tool, the pricking blade 3 serves as a piercer for making the first opening into the sheet metal into which the jaw 4 may be afterwards introduced in order to continue the cutting by moving the handle forward.

- 40 In the case where the sheet metal is very resistant or where the person using the tool

is too weak for punching a hole into the sheet an auxiliary tool may be used which forms also part of this invention. This tool comprises a wire 8 with a hook 9 at one end and a grip 10 having a hole into which said wire is inserted while the hook is introduced into the hole 7, provided in the handle 6 next to the cutter. While the grip takes hold of one edge of the tin can 50 11 the pricking blade 3 is applied to the opposite edge of the can so as to form a leverage with the handle 6. Thus even the weakest person may be enabled to thrust a hole into the can by means of a blade 3. 55

What I claim as my invention and desire to secure by Letters Patent is:

1. A can opener including a blade formed with a V-shaped cutting edge, a handle rigidly secured to the blade and extending away from the same, said handle being provided with an aperture adjacent to the blade, a wire having a hook at one end engaging said aperture, and a gripper mounted on the wire near its opposite end and adapted to grip the edge of the can. 65

2. In a tin can opener, in combination a cutter-blade formed with a knife-like sharply curved upper jaw and a toothed sharply curved lower jaw and with a two 70 edged pricking blade, a handle made of a metal strip having a U-shaped cross-section and provided with a hole adjacent to the blade, a wire provided with a hook at one end adapted to be introduced in the hole of said handle, and a gripper to take hold of a tin can's edge arranged slidably on said wire, all for the purpose set forth. 75

In testimony whereof I affix my signature.

CHARLES BAEHR.
